UNITED STATES PATENT OFFICE.

MYER S. SILVER, OF BOSTON, MASSACHUSETTS.

METHOD OF MAKING AUXILIARY HEEL LININGS.

Application filed October 16, 1926. Serial No. 142,008.

This invention relates to linings for shoes and more particularly to an auxiliary lining for the heel portion of a shoe, especially a low shoe, to prevent the same from slipping 5 up and down and chafing the foot.

Numerous attempts have heretofore been made to provide a satisfactory anti-slip lining of the general character in question, which will cling to the stocking and which 10 will also firmly adhere to the shoe and remain in the proper position. Linings have been made of cloth, of leather and of rubber. Although rubber is an excellent material on account of its non-slip properties, it has been 15 found in practice that it is practically impossible to secure the rubber lining to the shoe in such a way that it will remain in position and not work loose. Experiments have shown that ordinary adhesives will not effectively hold a rubber lining to the shoe. 20

The object of the present invention is to provide an improved method of making an auxiliary lining of the type referred to, which lining shall possess exceptional non-slip and 25 cushioning properties, and which will, at the same time, remain securely attached to the shoe counter for indefinite periods.

In order that the invention may be readily understood, reference is had to the accompanying drawing, forming part of this specification, and in which:—

Figure 1 is an enlarged fragmentary sectional view of the material from which my improved linings are manufactured;

Figure 2 is a similar view illustrating my first step in treating this material;

Figure 3 is a plan view showing how the blanks are cut from a sheet of material such as illustrated in Figure 2;

Figure 4 is a fragmentary sectional view on an enlarged scale, showing another step in the manufacture of my improved linings;

Figure 5 is a face view of one of my completed linings;

Figure 6 is a transverse section on an enlarged scale on the line 6—6 of Figure 5; and

Figure 7 is a perspective view showing the shape of my improved lining when in use.

Referring to the drawings in detail, the material from which I manufacture my improved linings consists of a sheet of soft rubber 1, preferably sponge rubber, to each face of which is permanently united or secured 55 a piece of fabric 2, such, for example, as

flannel or canvas. This fabric may be united to the sponge rubber by means of rubber cement or other waterproof strong adhesive, but I prefer to unite the rubber and fabric by means of vulcanization, that is to say, the 60 fabric is vulcanized directly to the sponge rubber.

The sheet consisting of the sponge or other soft rubber and fabric, as shown in Figure 1, is now coated on both sides with an adhesive such as glue or the like, as indicated at 3 in Figure 2. After the adhesive coated sheet has dried sufficiently, I then cut from it blanks of the desired shape, as indicated at A in Figure 3. These blanks are preferably 70 of the shape shown, having a rounded upper edge and provided in the middle of the lower edge with a V-shaped notch b, in order to enable the lining to better conform with the curve of the shoe heel. 75

After the blanks A have been cut out from the sheet, they are split centrally, as by means of a knife or the like X, in the manner shown in Figure 4, so that each blank forms a pair of linings. Each such lining, therefore, 80 comprises a facing 1^a or 1^b of sponge rubber, and a backing 2 of fabric coated with adhesive 3.

The finished lining is shown in Figures 5 and 6. In these figures is shown a lining 85 a having a sponge rubber facing 1^a and a fabric backing 2 provided with a coating 3 of adhesive.

Preferably the upper curved edge of the lining is thinned or beveled, as shown at c, 90 in order to facilitate inserting the heel into the shoe.

Figure 7 shows how my improved lining appears when bent to a shape to fit inside of the heel of a shoe. In practice, the outer surface 3 of the lining is moistened to soften the adhesive and the lining is then placed in position in the shoe.

I find that the glue or adhesive forms a secure and permanent bond between the fabric 10 fabric 2 and the shoe, and thus, the fabric being firmly united to the rubber, by vulcanizing or otherwise, the rubber is effectively held in position and prevented from working loose. In other words, the difficulties heretofore encountered in connection with rubber linings are overcome by interposing a piece of fabric between the rubber and the shoe, the fabric being firmly united with the rubber. 105 I find that the adhesive will effectively 110

stick to the fabric and hold the same in the shoe, while experience has shown that it will not stick to or properly hold rubber alone.

What I claim is:—

- 5 1. The method of making auxiliary heel linings which comprises forming a sheet of sponge rubber between two pieces of fabric to which the rubber is vulcanized, cutting from such sheet blanks of the desired shape,
- 10 and then splitting each blank to form a lining having a face of sponge rubber and a fabric backing.
- 15 2. The method of making auxiliary heel linings which comprises forming a sheet of sponge rubber between two pieces of fabric to which the rubber is vulcanized, coating the fabric on both sides of the sheet with ad-

hesive, drying the same, cutting from such sheet blanks of the desired shape, and then splitting each blank to form a lining having a sponge rubber face and a backing of adhesive coated fabric. 20

3. The method of making auxiliary heel linings which comprises securing a piece of fabric to each side of a sheet of sponge rubber, 25 coating the outside of the fabric on both sides of the sheet with adhesive, drying the same, cutting from such sheet blanks of the desired shape, and then splitting each blank to form a lining having a sponge rubber face 30 and a backing of adhesive coated fabric.

In testimony whereof I affix my signature.

MYER S. SILVER.
